UNITED STATES PATENT OFFICE

134,959

DESIGN FOR A LAPEL EMBLEM BUTTON OR THE LIKE

William S. Knudsen, United States Army, Washington, D. C., assignor to the United States of America, as represented by the Secretary of War

Application November 11, 1942, Serial No. 108,748

Term of patent 3½ years

To all whom it may concern:

Be it known that I, William S. Knudsen, Lieutenant General, United States Army, a citizen of the United States, now stationed at Washington, in the District of Columbia, have invented a new, original, and ornamental Design for a Lapel Emblem Button or the like, of which the following is a specification, reference being had to the accompanying drawing, forming part thereof.

Fig. 1 is a plan view of a lapel emblem button or the like, showing my new design; and

Fig. 2 is an edge elevational view of the same. The essential features of my design reside in the portion shown in full lines.

While I have shown my design embodied in the form of a button, it is understood that the same may be embodied in other similar articles without departing from the scope of my invention.

I claim:

The ornamental design for a lapel emblem button or the like, as shown and described.

WILLIAM S. KNUDSEN.
